[57] CLAIM

The ornamental design for a chair arm, as shown and described.

DESCRIPTION

FIG. 1 is a perspective view of a chair arm, showing my new design, the broken lines are for environmental purposes only and forms no part of the claimed design; FIG. 2 is a front elevation view of the left arm thereof; FIG. 3 is an outside elevation view thereof; FIG. 4 is a rear elevation view thereof; FIG. 5 is an inside elevation view thereof; FIG. 6 is a top plan view thereof; and, FIG. 7 is a bottom plan view thereof. The corresponding views of the right arm are the mirror images of the left arm as shown.
